[57] CLAIM

The ornamental design for a combined fire hose and cabinet therefor, as shown and described.

DESCRIPTION

FIG. 1 is a front elevation view of a combined fire hose and cabinet therefor showing my new design;

FIG. 2 is a front elevation view thereof in which the door is open;

FIG. 3 is a top plan view thereof;

FIG. 4 is a bottom plan view thereof;

FIG. 5 is a side elevation view thereof;

FIG. 6 is a side elevation view thereof opposite to that of FIG. 5;

FIG. 7 is a rear elevation view thereof.
